UNITED STATES PATENT OFFICE.

WARREN W. CARPENTER, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed January 19, 1924, Serial No. 687,346. Renewed April 5, 1926.

This invention relates to telephone exchange systems and more especially to systems involving the use of automatic switching equipment for setting up connections.

5 In systems where controlling mechanisms, common to a number of selective switches, are employed for controlling the operation of said switches it becomes necessary, whenever a particular switch is taken into use, 10 to associate the controlling mechanism with such switch for the time being in order that the switch may be governed in its selective operation.

Accordingly it is an object of the present 15 invention to selectively associate the switch controlling mechanism with the proper one of a number of switches to establish a connection through such switch.

A feature of the invention relates to 20 means for connecting a common control mechanism to a circuit incoming to any one of a number of switches together with separate means for selectively connecting the mechanism to such switch for controlling 25 the same.

Another feature of the invention relates 30 to a system having a number of groups of switches with a plurality of trunks incoming to said switches and a controlling 35 marker common to all groups and associable with any trunk for receiving a record together with means for then connecting the marker to the proper switch in the proper group for controlling the operation thereof.

40 Another object of the invention is an improvement in registering and controlling devices of the type employed in systems of the foregoing character arranged to guard against failures and improper operations.

45 A further feature of the invention according to this object is to provide, in a mechanism where records are registered on one register device and then transferred to another register device comprising relays, means for determining if said registers are 50 operating properly.

Referring to the drawing, Figs. 1 and 2 taken in order with Fig. 3 below Fig. 1 and Fig. 4 below Fig. 2 illustrate a sufficient 55 portion of a telephone system to enable an understanding of this invention.

Fig. 1 shows diagrammatically a line switch of the coordinate type, one of a number of trunks outgoing therefrom to-

gether with a sender selector switch, also 55 schematically illustrated.

Fig. 2 shows a portion of a first group selector switch of the coordinate type in which terminate the trunks outgoing from 60 the line switches.

Fig. 3 shows in schematic form one of a number of common register senders together with a connecting device for associating the register senders with marker controlling mechanisms.

To the left of the broken line in Fig. 4 there is illustrated one of the common marker controlling devices. To the right of the broken line in this figure there are shown two of the number of frame connectors, each of which serves to connect the marker mechanisms with a different group of selector switches such as shown in Fig. 2.

Fig. 5 is a schematic illustration showing 70 the arrangement of the equipment.

General description of circuits and apparatus.

A general understanding of the system and the objects accomplished therein may best be had by first considering the diagram of Fig. 5. The subscribers' lines 501, 502, etc., enter the exchange and terminate in a sufficient number of coordinate line switches, one of which, switch 500, is shown. 80

The trunks outgoing from these line switches are distributed among a number of groups of first or district selector switches. In the diagram two of these groups are illustrated each comprising two 85 switches. For instance, the first group is made up of the two district switches 507 and 508, whereas the second group consists of the two switches 509 and 510. The

trunks outgoing from the line switches are 90 distributed among the switches in these groups. The two trunks 503 and 504, for example, outgoing from the line switch 500 enter respectively, district switches 509 and 510 of the second group. Similarly, the

trunks 505 and 506 appear, respectively, in the switches 507 and 508 of the first group. In a similar manner other trunks outgoing from the line switch 500 and from other line switches will be distributed among the 95 various selectors of the various groups.

The controlling equipment for governing the selective operation of the district

switches consists of subscribers' senders and controlling markers, one sender 514 and two markers 516 and 520 being illustrated. The sender 514 is common to a plurality of calling lines and the markers 516 and 520 are common to all of the district selector switches in all groups. The sender 514 may be associated with any one of the trunks outgoing from the line switches by means of a coordinate sender selector switch 513. Thereafter the sender 514 through a connecting device 515 is connected to one of the controlling markers such as marker 516.

At this point it becomes necessary to connect the controlling marker 516 to a particular one of the district selector switches in order to selectively operate said switch to extend a calling line over an outgoing trunk to the switch beyond. The outgoing trunks leaving switches of the first group are represented by the group 511, whereas the group of trunks 512 are the ones outgoing from the switches in the second group. For the purpose of connecting the marker to the district selector switches there are provided a number of frame connectors 517, 518, etc. The frame connector 517 serves to connect the markers to the switches of the group containing the selectors 507 and 508. Likewise, the frame connector 518 serves to connect the markers to the group containing the switches 509 and 510. Consequently, it is necessary to determine which one of the two frame connectors shall be employed in order that the marker may be connected to the proper group of switches. If the calling subscriber's line is extended over the trunk 505 which appears in the switch 507 in the first group, then the frame connector 517 is selectively operated to connect the marker 516 to the switch 507. In like fashion, if the calling line is extended over the trunk 503 to the switch 509, the frame connector 518 will be selectively operated instead to connect the marker 516 to the selector 509. Since the frame connectors 425 shown in Fig. 4 and 426 are separate devices two markers may be connected to selectors at the same time. Obviously other frame connectors may be provided for other groups of selectors.

Referring to the circuit drawings, the subscribers' lines terminate in vertical rows of contacts in the line switches 100. For instance, line 101 together with other lines appear in the vertical row 114, whereas still other lines appear in other vertical rows of contacts. The trunks 103, 104, etc., appear, respectively, in vertical rows of contacts 115 and 116 each trunk being accessible through all of the link circuits 102, 118, etc.

The trunk 104 leaving the line switch 100 appears in the vertical row of contacts 201 of the district selector switch 200, having

access to all of the horizontal links 205, 206, 207 and 208. A second trunk 210, which may come from any one of the line switches, appears in the vertical row of contacts 202 of the selector 200. The selector switch 200 is also equipped with a number of groups of trunks outgoing to succeeding selector switches (not shown). The trunks occupying the vertical row of contacts 203, each having an appearance before a single one of the respective horizontal links, may represent one of these groups. Similarly, a second group of trunks may occupy the second vertical row of contacts 204. Each of these trunks, such as the trunk 225, is multiplied to appear in a corresponding position in other district selector switches.

The trunk 104 is shown having an appearance in the sender selector switch 110. Other trunks will similarly appear in the sender selector switch. The selector switch 110 has access to a plurality of subscribers' senders one of which is illustrated in Fig. 3.

The register sender, among other elements, consists of a plurality of relay registers, three of which, 305, 306 and 307, are illustrated. The purpose of these registers is to take the digits transmitted by the calling subscriber and make a record thereof.

The marker illustrated in Fig. 4 consists of a number of relay registers 400, 401, 402 corresponding with the registers of the sender together with other controlling equipment.

A connecting device 320 is provided for connecting any of the common register senders with the markers. This device may consist of a multi-contact relay structure which serves to connect the various leads from the sender through to the corresponding leads in the marker. For an understanding of the general arrangement and operation of the subscriber's sender, the switch controlling marker and the multi-contact relay device 110 for interconnecting the same, reference is made to the application of W. W. Carpenter, Serial No. 703,362, filed April 1, 1924.

The controlling marker is connected to a district selector frame 200 by means of frame connectors 425 and 426. Frame connector 425 comprises a number of multi-contact relays 427, 428, 429 and 430. The relay 427 is individual to the particular district selector shown in the drawing. Relay 428 and other relays are respectively individual to other district selector switches contained in the same group. Relay 430 is individual to the marker mechanism shown in the drawing. In like manner, the relay 429 serves to connect another similar marker to any of the district selector switches of this group.

Similarly the frame connector 426 serves to connect the markers to the several district selector switches of the second group.

As above mentioned, the switches 100, 200 and 110 are of the coordinate type comprising essentially a plurality of horizontal link circuits which interconnect incoming lines or trunks and outgoing lines or trunks together with cooperating bars and magnets for effecting the connections. Referring to the district selector switch 200, the link circuits 205, 206, 207, and 208 constitute a portion of the total number of links in the switch all of which serve to connect the incoming trunks to the outgoing trunks of the different groups. The vertical bars 211, 212, 213, 214 are associated respectively with the vertical rows of contacts 201, 202, 203 and 204. These bars are operated under the control of individual magnets 218, 219, 220 and 221. The horizontal bars 215, 216, 217, etc. are operated by the respective magnets 222, 223, 224 which cooperate with the vertical bars to establish and hold the connection through the switch. The construction and operation of these switches may be of the general character illustrated in the patent to S. B. Williams, No. 1,517,331, granted December 2, 1924.

Referring particularly to the registers of the sender and the marker it will be noted that each of these constitutes four separate relays. In the sender the register 305 comprises the four relays 308, 309, 310 and 311; the register 306 comprises the relays 312, 313, 314 and 315 and the register 307 includes the relays 316, 317, 318 and 319. These relays are operated in various combinations depending upon the value of the digit which they are to record.

In the marker, the register 400 comprising relays 403, 404, 405 and 406 corresponds to the register 305 in the sender. The register 401 including relays 407, 408, 409 and 410 corresponds to the register 306 of the sender. Lastly the register 402 in the marker comprising relays 411, 412, 413 and 414 corresponds to the register 307 of the sender. After the digits have been recorded on the registers of the sender it then becomes necessary to transfer this record to the marker by operating relays in the registers of the marker which correspond to the operated relays of the registers of the sender. In this way the record is transferred from the sender to the marker in order that the marker may govern the operation of the switch accordingly. Inasmuch as the circuits for operating the marker register relays all lead through contacts in the connecting device 320, it may sometimes happen that due to a defective contact the proper relays in the marker are not operated. The result of this, if the apparatus were permitted to continue functioning, would be to set up a false connection. Accordingly provision is made whereby a test may be made each time a record is transferred from the sender to the

marker to ascertain whether it has been correctly transferred. The manner in which this is accomplished will be described in detail hereinafter.

Detailed operation of system.

When the subscriber of the calling line 101 removes his receiver, the line switch 100 is operated automatically to extend the calling line to an idle trunk 104. Furthermore the sender selector switch 110 is automatically operated to connect the selected trunk 104 through to the idle register sender illustrated in Fig. 3. While the sender selector switch 110 is undergoing operation, a circuit is completed for relay 106 from a ground applied at the sender selector switch and this relay operates. Relay 106 closes on obvious circuit for the slow release circuit 108. Furthermore relay 106 completes an impulse circuit from the calling subscriber's line, through to the register sender. This circuit may be traced from battery, through the winding of the impulse relay 300, contacts of the switch 110, conductor 120, lower contact of relay 106, over the ring side of the trunk 104, through the switch 100, over the subscriber's loop returning through the switch 100, tip of the trunk 104, upper contact of relay 106, conductor 121, contacts of the switch 110, through the coil 301 to ground. The manner in which the line switch 100 is operated to select an idle trunk and in which the selector switch 110 is operated to associate the trunk with an idle sender is fully described in the patent to S. B. Williams, No. 1,517,331, granted December 2, 1924.

The impulse relay in operating completes an obvious circuit for the slow relay 302. The relay 302 is the holding relay and applies ground potential to conductor 326 which leads through the sender selector to conductor 122, whereby the relay 106 is held energized.

The subscriber now manipulates his transmitter to send a series of impulses representing the number and designation of the called line. The relay 300 responds to these impulses, and causes the setting of the registers 305, 306 and 307, etc. After the registers have been positioned the connecting device 320 is operated to connect the register sender through to the marker illustrated in Fig. 4. The manner in which the registers 305, 306 and 307 are positioned under the control of the impulse relay 300, and the manner in which the sender is associated with the marker through the connecting device 320 may be in general the same as that described in detail in the patent to S. B. Williams, No. 1,517,331, granted December 2, 1924, and in the application of W. W. Carpenter, Serial No. 703,362, filed April 1, 1924.

It will be assumed that the designation recorded on the registers of the sender calls for the operation of relays 308 and 310 of the register 305, relays 313 and 315 of the register 306, and relay 316 of the register 307.

With this record established in the sender, one of the first operations to take place following the connection of the sender to the marker is to transfer the record to the corresponding registers 400, 401 and 402 of the marker. At the time the sender is connected to the marker, a holding relay 424 is operated for the purpose of applying a general holding ground potential for the various relays involved in the marker. Relay 424 completes an obvious circuit for relay 417. Relay 417 closes a circuit from ground through its contacts, contact of relay 415, contacts of the device 320, thence through the windings of relays 321, 322, 323 in parallel to battery. Relay 321 applies ground potential through its contacts to conductors 327, 328, 329 and 330. These conductors lead through the connecting device 320 to the windings of relays 403, 404, 405 and 406 of the register 400. Consequently, the relays of register 400 all operate. Relay 322 connects ground through its contacts to the conductors 331, 332, 333 and 334. These conductors lead through the connecting device 320 to the windings of the respective relays of the register 401 in the marker. Accordingly, all of these relays are operated. Furthermore, the relay 323 applies ground potential through its contacts to its conductors 335, 336, 337 and 338, which extend through the connecting device 320, to the windings of relays 411, 412, 413 and 414. These relays are all operated.

With all of the relays of register 400, 401 and 402 energized, a series circuit is completed from ground at the right contact of relay 403, thence through the right contacts of relays 404, 405, 406, 410, 409, etc. finally through the winding of relay 416 to battery. Relay 416 operates and locks to ground at the contact of relay 417. Relay 416 completes an obvious circuit for relay 415. Relay 415 opens the circuits of relays 321, 322 and 323 and these relays release.

Relays 321, 322, 323 when released remove ground potential from the various conductors, opening the energizing circuits traced for the register relays in the marker. All of these relays release, except the ones which correspond to the energized relays in the registers 305, 306 and 307 of the sender. Relay 403 which corresponds to relay 308 does not release since it is held in a circuit completed through the contact of relay 308. Relay 405 does not release since it is held in a circuit completed through the contact of relay 310. Similarly, relays 408, 410 and

411 do not release, inasmuch as they are held energized in circuits completed respectively through the contacts of relays 313, 315 and 316.

Thus all of the relays in the marker have been energized, and immediately thereafter all of the relays thus energized are released, excepting the ones which correspond to the energized relays of the registers in the sender. In this way a test is made of all of the circuits for the register relays in the marker, which lead through the contact points of the connecting device 320. If these circuits are all intact, as they should be, all of the relays are operated, and the series circuit is completed for operating the relay 416. If on the other hand, there is a defective contact in any one of the circuits, the corresponding register relay fails to operate, and the series circuit is not completed, whereby relays 415 and 416 cannot operate. The failure of these relays to operate may serve as an indication that the marker should not proceed with the establishment of the connection.

A description will next be given of how the marker is selectively connected through one of the frame connectors 425 and 426 to the proper district selector frame 200. Inasmuch as the trunks leading from the line switches may be distributed among the district selectors of the switch groups, it is necessary that the marker should be connected to the particular district frame to which leads the trunk over which the calling line has been extended. In the present instance, the calling line has been extended over the trunk 104 which terminates in the district frame 200. The district selector 200 along with the others in the same group is served by the frame connector 425. Therefore, it becomes necessary to give the marker some indication telling it that it should make connection through the frame connector 425 to the selector switch 200.

Inasmuch as the trunks coming from the line switch each appear in a single one of the district switches, these trunks may be taken as a means of identifying the particular switch through which the connection must be extended. Therefore, by giving all of the trunks leading to a group of district switches one kind of a characteristic identification which is different from the identification given the trunks leading to each and every other group, the necessary information may be given the marker to enable it to employ the proper one of the frame connectors. This characteristic identification consists of circuits including resistances 112 and 113 connected to the contacts of the relay 111, individual to each of the trunks leading to the district switches. The particular resistances 112 and 113 shown are individual to the trunk 104. The

resistance 112 may be low, and the resistance 113 may be high for every other trunk leading to the switch 200, and to all of the switches of the same group. A different combination of resistances will be employed for the trunks leading to another group of switches. For instance, for a particular group the resistance 112 may be high and the resistance 113 may be low. For still another group the resistance 112 may be omitted. For still another group the resistance 113 may be omitted, etc.

When the sender is connected to the marker, the indication relating to the district group is recorded in the marker as will now be explained. First a circuit is completed from battery, through the high resistance 113, outer left back contact of relay 111, conductor 123, contacts of switch 110, conductor 340, contact of relay 303, through contacts of the device 320, winding of the relay 423, winding of relay 420, contacts of relay 421 to ground on the holding conductor 435. Since the resistance 113 is high, only relay 420 operates. Still another is closed from battery through the low resistance 112, inner left hand back contact of relay 111, conductor 124, contacts of switch 110, conductor 341, contact of relay 303, contacts of device 320, marginal relay 422, relay 419, to the grounded conductor 435. Due to the low resistance 112, the marginal relay 422 operates and relay 419 also operates. With relays 419 and 420 operated, an obvious circuit is closed for operating the relay 418. With relay 418 operated, a circuit is closed for the relay 432 at the frame connector 425 which is individual to the marker shown. The circuit for this relay may be traced from ground over conductor 435, contact of relay 421, contact of relay 418, front contact of relay 422, outer back contact of relay 423, winding of relay 432 to battery. Relay 432 closes a circuit for relay 431 which may be traced from battery through the lower winding of relay 431, upper front contact of relay 432, back contact of relay 433 to grounded conductor 435. Relay 431 locks in a circuit from battery through its upper winding and contact, winding of relay 433, lower contact of relay 431, lower contact of relay 432, to the grounded conductor 435. Relay 433 also operates in this circuit. Relay 431 at its upper back contact opens the circuit to prevent succeeding similar relays from locking. The multi-contact relay 430, which is individual to the marker shown is now operated in a circuit from battery, through its winding, upper contact of relay 431, front contact of relay 433, to the grounded conductor 435.

At the time the marker was connected to the sender a circuit is extended back through the connecting device 320 of conductor 342,

thence through the sender selector 110, outer back contact of relay 111, through the winding of the vertical operating magnet 218 which controls the vertical row of contacts 201, in which appears the trunk 104. The manner in which this circuit is established is described and illustrated in the patent to S. B. Williams, No. 1,517,331, granted December 2, 1924. The magnet 218 rotates the vertical bar 211 to prepare all sets of contacts in the vertical row 201. Furthermore, the magnet 218 completes a circuit through its contacts over conductor 226, through the winding of the multi-contact relay 427 of the frame connector 425. It will be noted that the multi-contact relay 427 will be operated whenever one of the vertical magnets 218, 219, etc. in the switch 200 is operated. Thus the relay 427 identifies the particular district selector 200, and since the marker is already connected through the relay 430, the relay 427 further extends the connection to the operating parts of the selector switch 200.

In a manner fully described in the patent to S. B. Williams, No. 1,517,331, granted Dec. 2, 1924, the vertical magnet 220 relating to the proper group of outgoing trunks is operated, the horizontal link circuits are tested and the proper horizontal magnet is operated to extend the trunk 104 through a link circuit, and thence over the selected outgoing trunk 225 to the switch beyond. These operations are effected over the conductors such as the conductors 437 which lead from the marker through the frame connector 425 directly to the operating parts of the frame 200. Immediately, after the connection is effected, a holding circuit is completed from battery through both windings of the horizontal magnet 227 (assuming the connection was extended over link 205) through contacts of the switch thence over the sleeve conductor 125 to ground at the contact of relay 108.

After the connection has thus been extended the vertical magnets 218 and 220 are released. The magnet 218 releases the relay 427 and the marker is disconnected from the frame 200.

Had the calling line been extended to a district selector in some other group a different combination of the relays 419, 420, 422 and 423 would have been operated, resulting in the operating of a relay such as relay 434 associated with the frame connector 426.

After the connection has been established, and the sender is no longer required, it may be released and freed from the trunk circuit 104. At this time the relay 106 releases, and the calling line is extended through to the left hand windings of the repeating coil 105. Relay 107 operates and closes a substitute holding circuit for relay 108, which

maintains ground connection on the holding conductor 125.

When it is desired to release the connection the subscriber replaces his receiver on the switchhook and relay 107 releases. The relay 108 which removes the holding ground from the conductor 125 permits the operated switches to be released.

The invention claimed is:—

10. 1. The combination with a telephone line of a number of selective switches, a plurality of trunks leading to each switch, said trunks varying in character, means for extending said line over any one of said trunks to said switches, a controlling marker, a switch for associating the extended line with said marker, a connector for each selective switch for connecting said marker thereto, means depending upon the character of the trunk over which said line is extended for selecting one of said connectors, means for operating the selected connector to connect said marker to the corresponding selective switch, and means governed by said marker for selectively operating the switch.
15. 2. The combination with a line of a number of selective switches, a plurality of trunks leading to said switches, resistance elements for said trunks for giving each trunk a characteristic differing from other trunks, means for extending said line over one of said trunks to one of said switches, a controlling marker common to said switches, means for associating said marker with the extended line, a connector for each of said switches for connecting said marker thereto, means dependent upon the resistance elements associated with the trunk over which the line is extended for selecting one of said connectors, and means controlled by the marker for selectively operating the switch to which it is connected.
20. 3. The combination with a telephone line of a number of groups of switches, a plurality of trunks leading to each switch, all trunks leading to the switches of each group having a characteristic differing from the trunks leading to other groups, a controlling marker, means for associating the extended line with said marker, a connector for each group of switches for connecting said marker to any one of the switches thereof, means dependent upon the characteristic of the trunk over which the line is extended for selecting one of said connectors for operation, and means controlled by the marker for selectively operating the particular switch to which it is connected.
25. 4. The combination in a telephone system of a plurality of registers for receiving a record, a second plurality of registers, means for connecting the first registers to the second registers, means for transferring the

record from the first to the second registers 65 by operating said second registers in accordance with the operated condition of said first registers, and means for determining if said second registers are operating properly.

5. The combination in a telephone system 70 of a plurality of registers for receiving a record, a second plurality of registers, means for connecting the first registers to the second registers, means for transferring the record from the first to the second registers 75 by operating said second registers in accordance with the operated condition of said first registers, and means controlled by the second registers for determining if they are operating properly.

6. The combination in a telephone system 80 of a set of registers for receiving the record, a second set of registers, means for connecting the first set of registers to the second set of registers, means for operating all of the registers of the second set and releasing all of said registers, excepting the ones corresponding to the operated registers of the first set, and means rendered effective if all 85 of the registers of said second set operate properly.

7. In combination a set of relay registers, a second set of relay registers, means for operating the relays of said first set to establish a record thereon, means for connecting the first set to the second set, means for operating all of the relays of the said second set initially, means for releasing all the relays of said second set, excepting those which correspond to operated relays of the first set, and a relay controlled through contacts of 100 all of said relays of the second set in their operated conditions.

8. In combination, a set of relay registers, means for operating said relays to establish a record thereon, a second set of relay registers, a connecting device for connecting said sets of registers together, means for closing circuits through the contacts of said connecting device for operating all the relays of said second set, means for holding operated all relays of the second set corresponding to the operated relays of the first set, and means responsive jointly to all of said 115 relays of the second set when in their operated condition.

9. The combination with a telephone line of a number of selective switches, a plurality of trunks leading to each switch, a combination of high and low resistance elements associated with each of said trunks for giving each trunk a characteristic differing from other trunks, means for extending said line over one of said trunks to one of said switches, a controlling marker common to said switches including therein a plurality of relays, means for associating the 120 125

marker with the extended line, a connector means controlled by the marker for selectively operating the switch to which it is connected. In witness whereof, I hereunto subscribe my name this 18th day of January A. D., 1924.
